UNITED STATES PATENT OFFICE.

FRANK M. GUSTIN, OF DURAND, MICHIGAN.

WINDOW-SCREEN.

1,123,276.

Specification of Letters Patent.

Patented Jan. 5, 1915.

Application filed August 27, 1913. Serial No. 786,874.

To all whom it may concern:

Be it known that I, FRANK M. GUSTIN, citizen of the United States, residing at Durand, in the county of Shiawassee and State of Michigan, have invented certain new and useful Improvements in Window-Screens, of which the following is a specification.

The present invention relates to new and useful improvements in window screens, and has particular reference to that type of such devices which are adjustable.

As its principal object, the present invention contemplates the provision of a window screen so constructed that it may be expanded or contracted either vertically or horizontally, to adapt it for application to windows of any height and width, within a reasonable range.

An object of equal importance with the foregoing is to construct a screen of this character with such regard to number, proportion and arrangement of parts that it may be cheaply manufactured, will be durable and efficient in its action, and may be applied to any window casing of the usual type.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts, Figure 1 is a front elevation illustrating the screen in assembled position in a window casing and illustrated with the two major sections in horizontal alignment. Fig. 2 is a front elevation illustrating the frame in assembled position within a window casing, with the major sections in vertical alignment. Fig. 3 is a perspective view of the screen in disassembled relation with the two major sections in horizontal alignment illustrating the major sections in extended position and further disclosing the minor sections composing the two major sections in slightly extended position. Fig. 4 is a section on the line 4—4 of Fig. 1. Fig. 5 is a detail fragmentary section of a corner of the female

major section illustrating particularly the manner in which the male and female minor sections of which the female major section is composed are slidably interfitted. Fig. 6 is a detail fragmentary section of the male major section, disclosing particularly the manner in which the male and female minor sections of which the male major section is composed interfit. Fig. 7 is an enlarged perspective view illustrating the two minor sections of the female major section extended approximately to the limit of their adjustment. Fig. 8 is an enlarged fragmentary perspective of the male major section. Fig. 9 is a detail fragmentary view illustrating the male and female sections of the female major screen section in disassembled relation disclosing particularly the manner in which the interfitting flanges of the two sections are slidably connected.

Proceeding now to the description of the drawings the numerals 10 and 11 designate respectively, and as entireties, the two major sections of which the screen is formed. Each major section consists of a pair of separate elements, substantially rectangular in shape, which are adjustably and slidably connected.

In the preferred embodiment the two major sections are in turn slidably and adjustably connected, it being therefore, apparent that when the major sections are arranged one above the other as in Fig. 1, they may be adjusted with such relation to each other that they will completely close the window space. It will also be obvious upon reference to Fig. 2 that when mounted in horizontal alignment with each other the major sections may be expanded as when in vertical positions to permit their application to a window of any width. Similarly it will be observed that when the screens are superposed one upon the other in vertical position, as in Fig. 1, the elements comprising the two major sections may be adjusted to produce the desired width in the screens. It will be further observed that by adjustment of the elements of which the major sections are comprised, the screen when arranged horizontally as in Fig. 2, may be accommodated to windows of various heights, as well as being horizontally adjusted.

Taking up the detailed description of the major sections, the member 10 which constitutes the female section of the screen, includes in its preferred embodiment, two

interfitting minor sections, respectively, designated as entireties by the numerals 13 and 14. The minor section 13 of this female major section includes, as best illustrated in Fig. 7, a substantially rectangular frame, which is preferably made of sheet steel, although galvanized tin, or any other similar suitable material may be employed, and consists of top and bottom frame members 15 and 16 and a pair of connecting side-frame members 17 and 18. Wire screening, indicated at 19 is secured to the rectangular frame above described, by means of spaced tongues 20 carried on the members 16, 17 and 18 and a turned edge carried on the upper frame member 15. The turned edge and the stamped tongues are both bent after the screening is in assembled position to clamp the edges of the screen firmly against the rear face of the frame members 15, 16, 17 and 18. The turned edge of the upper frame member 15 is not discernible in the drawings, but is substantially similar to the turned edge 21 formed on the lower frame-member of the male section 14, as illustrated in Fig. 7, and its construction will therefore be apparent upon reference to this figure. This turned edge on the upper frame-member 15 and the spaced tongues 20 are preferably made of relatively thin material, accomplished by flattening or rolling them during the manufacturing of the screen, the purpose in mind being to permit the user of the screen to apply new screening whenever desirable by merely pulling the tongues and the turned edge out of binding engagement with the adjacent face of the frame-members 15, 16, 17 and 18, as will be readily understood upon reference to the drawings.

In order to accommodate the flanges carried by the male section 14, to be hereinafter described, so that the two sections of the female major screen section may be slidably connected, the side frame members 17 and 18 are provided with "panned down" flanges 22 and 23, respectively. The outer portions 24 of these flanges are, as will be readily discerned by reference to Fig. 9, directed at a slight angle to the body portion 25 of the flanges so that the flanges of the male minor section, one of which is designated at 26 in Fig. 9 may be easily inserted to lie between the portions 24 and 25 of the flanges 22 and 23. These members 22 and 23 are preferably of such width that their outer edges terminate at a point approximately one-third the distance across the face of the base-flange 27, carried by the lower frame member 16 and extending at right angles therefrom, as clearly illustrated in Fig. 7. The outer edge of this base flange 27 is directed upwardly at right angles to the body portion of the base flange and in parallel spaced relation to the member 16.

A cross-sectionally L-shaped strip 28 is mounted longitudinally of the base-flange 27 and is arranged with its vertical portion 30 in parallel spaced relation to the outer vertical or upturned edge 29 of the base flange, having its horizontal portion 31 disposed on the base flange 27 and securely fixed thereon. The free edge of the portion 31 carries an upwardly and inwardly directed lip 32 which is adapted to receive a straight edged flange or connecting strip carried by the male major section of the screen, as will be hereinafter fully described.

The male minor section of the female major section heretofore designated as an entirety, by the numeral 14, is similar to the member 13 with one exception, that the cross-sectional U-shaped receiving flanges 22 and 23 of the section 13 are replaced by a pair of straight edged flanges 33 and 34, which are adapted for insertion in the flanges 22 and 23, as will be readily apparent upon reference to Fig. 7, in which this feature of the invention is best illustrated. As stated, this section 14 is similar in every other respect to the member 13 and for purposes of clearness in description the base-flange, L-shaped strip, and the associated parts of the section 14 will be hereinafter designated by the same numerals, heretofore ascribed, to the corresponding parts of the section 13.

Relative to the manner in which the sections 13 and 14 of the major female sections are slidably connected, it will be noted upon reference to Fig. 7, that the straight edge flanges 33 and 34 of the member 14 are slidably mounted in the members 22 and 23 in section 13, so that the two sections may be quickly and easily extended or contracted, to meet the requirements of the conditions incident to the application of the screen.

Coming now to the description of the male major section, which as heretofore set forth, includes in the preferred embodiment, a pair of minor sections formed in the nature of interfitting male and female sections, the numerals 35 and 36, designate respectively, and as entireties, the male and female minor sections referred to.

The female section 36 includes a substantially rectangular frame which as best illustrated in detail in Fig. 8, comprises a pair of top and bottom frame members 37 and 38 and a pair of side frame members, one of which is indicated at 39 in Fig. 8. The two side-frame members 39 and the bottom frame members 37 carry screen retaining strips, one of which is indicated at 40 in Fig. 4, and is welded, soldered or otherwise secured to the rear face of the frame member, being provided with a plurality of spaced tongues similar to the members 20, heretofore described. A turned edge is formed on the rear face of the upper frame

members 38, being substantially similar to the turned edge, heretofore ascribed, to the frame members 15, as in Fig. 7. The screen 41 is applied to this female minor section 36 by pressing the tongues and turned edge to clamp the edges of the screen against the rear face of the frame. The side frame members 39 and the female section 36 are "panned down" to produce receiving flanges 42 similar to the members 22 and 23 of the section 13, heretofore described, as indicated at 42 in Fig. 4. These receiving flanges 42 receive the straight edge flanges 43 formed on the side-frame members of the section 35, as will be hereinafter more fully described in detail. The lower frame member 37 of the section 36 carries an outwardly directed straight edge flange 44 which is of such size as to be insertible in the L-shaped strip 28, and is adapted to be held against movement from the base thereof by the inwardly directed lip 32 as will be readily observed upon reference to Figs. 7 and 8. It has been found necessary to form a notch 45 in the lower end of the receiving flange 42 so that the inwardly directed lip 32 may be accommodated.

Passing now to the description of the male minor section 35 which is adapted to be slidably interfitted into the female section 36, it will be obvious upon reference to Fig. 8 that this member is substantially similar to the member 36 with the exception that the screening indicated at 46 is arranged on the inner face of the frame and the U-shaped receiving flanges 42 of the section 36 are replaced by the straight edge flanges 43. These flanges 43 are insertible in the receiving flanges 42 and permit the two minor sections 35 and 36, which comprise the male major section, to be adjusted to increase or diminish their longitudinal dimension.

From the foregoing it will be observed, particularly upon reference to Figs. 7 and 8, that the male major section may be slidably connected to the female major section and slidably adjusted therein by inserting the flanges 44 of the sections 35 and 36 in the strips 28 of the sections 13 and 14, so that when the two major sections are applied to a window in horizontal alinement, they may be extended or contracted to correspond to the width of the window. It will further be noted that inasmuch as the upper and lower edges of the two major sections are firmly connected when in assembled relation, the minor male sections 14 and 35 of the two major sections may be simultaneously inserted farther within the receiving flanges 22, 23 and 42, or withdrawn therefrom to impart to the screen the desired vertical dimension.

As a means for holding the screens in adjusted position there has been provided a

pair of spring-actuated latch devices which are designated as entireties by the numerals 47 and 48 and are respectively secured to the lower and upper frame members of the sections 36 and 35. As best illustrated in Fig. 8 each of these spring-actuated latching devices includes a pivoted pawl 49 which is retained within a rectangular metallic housing 50 by a pivot pin 51 and is normally held with its forward terminal 52 exteriorly of the housing by means of a latch-spring 53. The forward terminals 52 of this pawl is formed with a notch indicated at 54. This notch is adapted to receive inwardly extending studs or pins carried by the upturned edge portions 29 of the female section, one of these studs being indicated at 55 in Fig. 4. A plurality of these stud pins are provided as indicated in Fig. 7, and it will be apparent that the engagement of these pins in the notches 54 of the pivoted pawls 49 will operate to hold the male major section of the screen against farther inward movement into the female section. The pawl may be pressed inwardly against the tension of the spring 53 and disconnected from the studs 55 by manipulation of the finger pin 56 which extends laterally from the pawl and is received within a cutaway portion 57 when swung inwardly toward the frame members 37.

In reduction to practice, I have found that the form of my invention illustrated in the drawings and referred to in the above description as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What I claim is:—

1. In a screen, a pair of major sections slidably connected for extension or contraction, each of said sections including a minor male section and a minor female section, the male and female minor sections of each major section being slidably connected for extension or contraction with relation to one another, and the male minor sections of the two major sections being slidably connected to the female minor sections of the major sections whereby the major sections may be extended or contracted in a line at right angles to the line of adjustment of the minor sections, said male and female major sections being both adapted for use as a complete screen.

2. A screen including a major female section and a major male section slidably connected thereto, said female section including a minor female section and a minor male

section, said minor female section consisting of a rectangular frame having panned-down flanges formed on its vertical side members, said minor male section consisting of a rectangular frame having straight edge flanges formed on its vertical side members, said straight edge flanges being slidably received within the panned-down flanges of the minor male section, said major 10 male section including a minor female section and a minor male section, said last-mentioned minor female section consisting in a rectangular frame having panned-down flanges formed on its vertical side members, 15 said last-mentioned minor male section consisting of a rectangular frame having straight edge flanges formed on its vertical side members, said last-mentioned straight edge flanges being slidably received within 20 the last-mentioned panned-down flanges, base flanges formed at the upper and lower terminals respectively of the male and female minor sections of the female major section and straight edge flanges formed on 25 the upper and lower horizontal members of the male and female minor sections of the major male section, said last-mentioned straight edge flanges being receivable in the base flanges of the female major section. 30 3. A screen including a major female section and a major male section slidably received therein, base flanges formed on the upper and lower horizontal members of the female section, straight edge flanges formed 35 on the upper and lower horizontal frame members of the male section, a substantially cross-sectional L-shaped strip arranged on each of said base flanges, there being an inwardly directed lip formed on 40 the horizontal portion of each of the said strips, said strips being adapted to receive the straight edge flanges of the said male section, and yieldable locking means mounted on the straight edge flanges of the male

section and engageable with the base flanges 45 of the female section for holding said sections in adjusted position.

4. A screen including a major female section consisting of slidably connected minor male and female sections, a major male section 50 slidably received by the major female section and consisting of slidably connected minor male and female sections, base flanges formed on the upper and lower horizontal members of the female minor section, 55 straight edge flanges formed on the upper and lower horizontal members of the minor sections of the major sections, the edge portions of said base flanges being bent at right angles and provided with a plurality 60 of inwardly extending studs, and a locking device mounted on each of the straight edge flanges and engageable with the studs for holding the major female and male sections 65 in adjusted position.

5. A screen including male and female sections, said female section being provided with base flanges, said male section being provided with straight edge flanges received within the straight edge flanges, inwardly directed studs carried by the base flanges, a locking device carried by the straight edge flanges and engageable with the studs for holding the sections in adjusted 70 position, each of said locking devices including a substantially U-shaped housing, a pawl pivoted therein, a spring bearing against the inner face of the pawl and normally projecting the free end of the pawl beyond the housing, the free end of said 75 pawl being bifurcated whereby it may receive one of the said stud members.

In testimony whereof I affix my signature in presence of two witnesses.

FRANK M. GUSTIN. [L. S.]
